UNITED STATES PATENT OFFICE

2,446,781

COMB

Allan A. Norin, Chicago, Ill., assignor to Gaylord Products, Incorporated, Chicago, Ill., a corporation of Delaware

Application October 15, 1945, Serial No. 622,306

3 Claims. (Cl. 132—26)

1

This invention relates to combs and is more particularly concerned with combs of the type adapted for use in arranging and maintaining coiffures or for securing hats, flowers, and other objects on the hair.

This invention contemplates the provision of a comb of this type in which the several teeth are formed and arranged to coact with each other for firmly engaging the hair to prevent retrograde movement and displacement of the comb from the hair.

This invention further contemplates the provision of a hair retaining comb provided with two rows of teeth formed of resilient material and arranged in staggered relation. Each tooth is provided with a relatively wide body portion for overlapping contacting engagement with adjacent teeth, and is also provided with a shank portion of relatively narrow width and disposed in spaced relation to adjacent shank portions to define hair receiving pockets.

This invention further contemplates the provision of a comb of this type which may be inexpensively manufactured of plastic or thermoplastic material to provide a comb of attractive, ornamental appearance and of resilient, yet serviceable construction.

This invention further contemplates an improved method of forming a comb having two rows of teeth arranged in staggered relation. This is accomplished by forming a pair of backings having depending teeth, and then gluing the backings to each other with the teeth of one row arranged in contacting staggered relation with respect to the teeth in the other row.

This invention embodies other novel features, details of construction and arrangement of parts which are hereinafter set forth in the specification and claims and illustrated in the accompanying drawing wherein:

Fig. 1 is a front elevational view showing a comb embodying features of this invention.

Fig. 2 is a top plan view of same.

Fig. 3 is a transverse sectional view taken along the line 3—3 of Fig. 1.

Fig. 4 is a sectional view taken along the line 4—4 of Fig. 1.

Fig. 5 is a fragmentary front elevational view showing a modified form of this invention.

Referring now to the drawing for a better understanding of this invention, and more particularly to Figs. 1 to 4 therein, a comb 8 embodying features of this invention is shown as comprising a pair of backings 9 and 11 which are preferably cemented together at 12, but which

2

may be otherwise secured to each other, if desired. Each backing is provided with a plurality of similar depending teeth 13 arranged in equally spaced relation, and each tooth is formed with a relatively narrow shank 14 and a relatively wide body portion 16. As illustrated in Fig. 1, each shank is defined by concave side edges extending downwardly from the backing to merge with convex side edges defining the body portion 16. The convex side edges converge toward the outer end of the body portion to terminate in a pointed terminal 17.

As viewed in transverse section, and as illustrated in Fig. 3, the body portion 16 of each tooth 13 is formed with an arcuate inner surface 18 for contacting engagement with the inner surfaces 18 formed on the opposing adjacent teeth. In order to maintain each tooth 13 in yieldable contacting engagement with opposing adjacent teeth, a reinforcing rib 19 is provided to extend along the shank 14 from its body portion 16 to its backing. As illustrated in Fig. 1, it will be observed that the several teeth are formed and arranged to provide hair receiving pockets 21 between the side edges of adjacent shanks 14.

While a comb of the type thus shown and described may be constructed of various materials, it is preferably formed of plastic or thermoplastic material to provide the desired ornamental and attractive appearance and to form resilient teeth adapted to yieldably resist retrograde movement of the comb from the hair.

Fig. 5 illustrates a modified form of this invention in which a comb of the type heretofore shown and described is provided with apertures 22 extending longitudinally along the body portion of each tooth 23 to provide flexible side walls 24 adapted to be yieldably urged towards each other by the passage of hair through the throat defined by the side edges of the adjacent teeth.

While this invention has been shown in but two forms, it is obvious to those skilled in the art that it is not so limited but is susceptible of various changes and modifications without departing from the spirit and scope of the claimed invention.

I claim as my invention:

1. In a comb, a pair of backings, a row of teeth depending from each backing, means for adhesively uniting said backings to arrange the teeth of one row in contacting staggered relation with the teeth of the other row, said teeth having relatively narrow shanks defined by concave side edges to provide hair receiving pockets between

adjacent teeth, said teeth having body portions of relatively greater width defined by convex side edges merging with the concave side edges of said shanks and extending downwardly to terminate in pointed terminals, the convex side edges of the body portions of adjacent teeth being disposed in overlapping relation, the body portion of said teeth being concavo-convex in cross section with the convex surfaces of adjacent teeth normally disposed in contacting engagement and yieldably resistant to movement out of contacting engagement.

2. In a comb, a pair of backings, a row of teeth depending from each backing, means for adhesively uniting said backings to arrange the teeth of one row in contacting staggered relation with the teeth of the other row, said teeth having relatively narrow shanks defined by concave side edges to provide hair receiving pockets between adjacent teeth, said teeth having body portions of relatively greater width defined by convex side edges merging with the concave side edges of said shanks and extending downwardly to terminate in pointed terminals, the convex side edges of the body portions of adjacent teeth being disposed in overlapping relation, the body portion of said teeth being concavo-convex in cross-section with the convex surfaces of adjacent teeth normally disposed in contacting engagement and yieldably resistant to movement out of contacting engagement, and reinforcing ribs provided on the outer sides of said teeth shanks, the body portion of said teeth being formed with elongated openings to provide yieldably resistant side portions.

3. In a comb, a pair of backings, a row of teeth depending from each backing, means for adhe-

sively uniting said backings to arrange the teeth of one row in contacting staggered relation with the teeth of the other row, said teeth having relatively narrow shanks defined by concave side edges in 5 to provide hair receiving pockets between adjacent teeth, said teeth having body portions of relatively greater width defined by convex side edges merging with the concave side edges of said shanks and extending downwardly to terminate in pointed terminals, the convex side edges of the body portions of adjacent teeth being disposed in overlapping relation, the body portion of said teeth being concavo-convex in cross-section with the convex surfaces of adjacent teeth normally disposed in 15 contacting engagement and yieldably resistant to movement out of contacting engagement, and reinforcing ribs provided on the outer sides of said teeth shanks, the body portion of said teeth being formed with elongated openings to provide yieldably resistant side portions.

ALLAN A. NORIN.
